UNITED STATES PATENT OFFICE.

WILLIAM S. McLEWEE, OF YARDLEY, PENNSYLVANIA.

DESIGN FOR A GAS-LAMP BODY.

No. 37,715.

Specification for Design.

Patented Dec. 5, 1905.

Application filed April 19, 1905. Serial No. 256,494. Term of patent 14 years.

To all whom it may concern:

Be it known that I, WILLIAM S. McLEWEE, a citizen of the United States, residing at Yardley, in the county of Bucks and State of Pennsylvania, have invented a new, original, and ornamental Design for a Gas-Lamp Body, of which the following is a specification, reference being had to the accompanying drawing, forming part thereof.

The figure is a perspective view of a gas-lamp body, showing my new design.

I claim—

The ornamental design for a gas-lamp body, as shown.

WILLIAM S. McLEWEE.
